UNITED STATES PATENT OFFICE.

WALTER HENRY BROWNING, OF LONDON, ENGLAND.

LEAF OF LOOSE-LEAF BOOKS.

Application filed August 5, 1927, Serial No. 210,892, and in Great Britain May 3, 1927.

This invention has relation to leaves for use in loose leaf books or binders and has for object the provision of a leaf especially adapted for use in systems of bookkeeping in which the leaf is removed from the book or binder and placed in a typewriter or adding machine by which the entries are made. The invention further has for object the provision of a leaf which may be caused 5 to project beyond the other leaves of a book, or, in other words be "off set", for the purpose of providing ready and easy reference to such sheet.

A loose leaf, in accordance with this invention has a part of the one end cut away so as to form straight sided projections without undercutting and a hole through which the locking or binding post extends.

A loose leaf, in accordance with this invention, has at least two projections, the free edges of which are in alignment, and the intermediate cut-away portion has a free edge which is parallel with those of the projections. Or the cut-away portion is 20 shaped so that its edge extends or bulges towards an imaginary line joining the free edges of the projections: Parts of the edge of the cut-away portion may extend to such line and be aligned with the free edges of 30 the projections.

The hole for the locking or binding post of the binder or cover is preferably placed centrally of the two projections and may be such that it permits the leaf to be moved 35 sideways relatively to the locking or binding post so that a portion thereof projects beyond the other leaves, or, in other words, the leaf is "off set", and thus constitutes a marker.

40 In order that the invention, the object and nature of which have been set forth, may be clearly and readily understood, reference will now be made to the accompanying sheet of drawings on which four embodiments of the invention are illustrated.

45 Fig. 1 is a face view showing two leaves placed the one on the other, one being displaced relatively to the other or "off set".

Figs. 2, 3 and 4 are similar views to Fig. 50 1, each of leaves of modified form.

Referring to Fig. 1;

Each leaf 11 has a part of one end cut away so as to form two straight sided projections 12, 13 without undercutting. Each leaf 11 also has a hole 14 through which the locking or binding post of the binder or

cover extends. The free edges of the projections 12, 13 are aligned and the free edge of the cut-away portion is parallel with those of the projections 12, 13. The hole 14 is placed centrally between the projections 12, 13 whether the projections be of like or unlike width. In the embodiment illustrated, they are of unlike width, the projection 13 being the wider. When the leaves 11 are 60 made with projections 12, 13 of like width, ready and easy reference to any particular leaf is afforded by means of book markers. When the projections 12, 13 are of unlike 65 width, any particular leaf is rendered distinctive by "off setting" that leaf and this is accomplished by turning the leaf over so that its projections 13, 12 lie upon the projections 12, 13 of the next sheet. In Fig. 70 2 the free edge of the cut-away portion of leaf 11^a is such that parts 15, 16 extend directly from the inner parts or roots of the projections 12, 13 respectively, towards an imaginary line joining the free edges of the projections 12, 13. A part 17 of the 75 free edge of the cut-away portion extends to the imaginary line and such part is aligned with the free edges of the projections.

In Fig. 3 the leaves 11^b have three projections 12, 13', 18 and two holes 14, 19. The hole 14 is placed centrally between the projections 12, 13' and the hole 19 centrally between the projections 12, 18. Also in this leaf the part 15 of the cut-away portion does 80 not extend directly from the inner part or root of the projection 12 but is joined therewith by a part 20 which is parallel with the free edge of the projection 12. Ordinarily the leaves 11^b rest on or engage carriers or 85 posts which contact with the projections 12, 13'. Offsetting is effected by moving the leaf to the left so that the leaf rests on or engages the one carrier or post by means of the cut-away portion between the projections 13', 18 and rests on or engages the other carrier or post by means of the part 20. When a leaf is offset, its hole 19 coincides with the 90 holes 14 of the other leaves.

In Fig. 4 the leaves 11^c have only two projections 12, 13 and one hole 14', and the latter is of greater width than the correspondingly numbered hole in the other figures of the drawings. Also the parts 15, 16 of the cut-away portion are united with 100 the inner parts or roots of the projections 12, 13 by parts 20, 21, respectively, which 105

are parallel with the free edges of the projections 12, 13. Ordinarily a leaf engages or rests on the carriers or posts by means of the parts 20, 21 with the projection 12 contacting with one carrier or post and offsetting is effected by moving a sheet to the left so that the projection 13 contacts with the other carrier or post. The hole 14', by such movement, is in effect reduced to a size 10 approximating that of the correspondingly numbered holes in the other figures of the drawings.

What I claim is:—

1. A leaf for use in loose leaf books of 15 the post type having on one edge projections spaced apart to engage the outer sides of the posts and provided with a hole for the locking post between the projections.

2. A leaf for use in loose leaf books of the post type having on one edge projections 29 spaced apart to engage the outer sides of the posts, the edge of the part between the projections being parallel with the outer edges of the projections, and provided with a hole for the locking post between the projections. 25

3. A leaf for use in loose books of the post type having on one side projections which extend beyond the main portion of the edge of such side, the space formed by and between the projections being adapted to receive posts of the binder, and said leaf being provided with a hole in its main portion situated between the projections to receive the locking post. 30

Dated this 22nd day of July, 1927.

WALTER HENRY BROWNING
